F. Q. CUESTA,
NON-REFILLABLE BOTTLE;
APPLICATION FILED MAY 13, 1916.

1,229,895.

Patented June 12, 1917.

Fig. 1.

UNITED STATES PATENT OFFICE.

FRANCISCO QUINTANO CUESTA, OF HABANA, CUBA.

NON-REFILLABLE BOTTLE.

1,229,895.

Specification of Letters Patent. Patented June 12, 1917.

Application filed May 13, 1916. Serial No. 97,268.

To all whom it may concern:

Be it known that I, FRANCISCO QUINTANO CUESTA, a citizen of the Republic of Cuba, and a resident of Habana, Cuba, have invented a new and Improved Non-Refillable Bottle, of which the following is a full, clear, and exact description.

This invention relates to bottle closures and particularly to the type known as non-refillable and has for an object the provision of an improved simplified arrangement which will be inexpensive in the manufacture and which will permit the free flowing of fluid from the bottle while resisting re-filling of the bottle.

Another object in view is the provision of a closure member which is connected with and forms part of the neck of a bottle and arranged so that there will be a movable valve and various guarding means for preventing the actuation of said valve except by the fluid in the bottle.

A still further object in view is to provide a closure in which there is a valve for preventing refilling and guarding means which also act in the capacity of means forming an air check.

In the accompanying drawing:

Figure 1 is a longitudinal vertical section through the upper part of a bottle and the neck, disclosing an embodiment of the invention.

Fig. 2 is a detail perspective view of a slightly modified form of valve member to that shown in Fig. 1.

Referring to the accompanying drawing by numerals, 1 indicates the bottle which may be of any shape and size and which is provided with a neck 2 formed with a reduced portion 3 whereby an annular shoulder 4 is presented. An annular ring 5 is arranged interiorly of the neck 2 and acts as a support for the cylindrical valve member 6, which valve member is cylindrical or tubular and open at the lower end. Near the upper end a plurality of apertures 7 are provided in the valve member 6 through which will flow the fluid from the bottle 1 when the bottle is inverted by reason of the fact that the weight of the fluid will move the valve member 6 downwardly and past the upper edge 8 of neck 2, against the action of spring 9. Spring 9 has been shown as being formed from a single member and coiled at the outer end, but it is evident that any form of spring could be

used without departing from the spirit of the invention, the use of this spring being only for holding the valve member closed against the action of air and also to insure the closing when only part of the fluid has been removed.

Associated with the neck 2 is an auxiliary neck 10 provided with a dividing web 11 merging into a tubular member 12 which in turn merges into a round or disk-shaped casing 13 which casing is provided with a number of apertures 14 facing toward the valve 6. The auxiliary neck 10 is provided with a hollowed-out part at the bottom fitting over the neck 2 and resting on the flange 4. This auxiliary neck may be secured rigidly in position in any suitable manner, as for instance, by being cemented thereto. The casing 13 is preferably made sufficiently large so as to approach the sides of the auxiliary neck 10 but leave an annular passage 15 through which the fluid may pass when emptying the bottle. When the bottle is in a horizontal plane spring 9 holds the valve member closed and also immediately closes the valve member when set upright after having been inverted, thus preventing the entrance of any fluid into the bottle 1. In addition to these features it will be observed that by the arrangement of the apertures 14 and the way the casing 13 and tubular member 12 are formed, an air trap is provided in the space 16 which will assist in preventing the flow of fluid and also which will assist the spring 9 in closing the valve member 6 in case it is attempted to force fluid into the bottle while in an inverted position.

In Fig. 2 a slight modified form of valve 95 is disclosed, in which it will be observed that the valve 6' is provided with a disk-shaped member 17 which will fit in the neck 2 when in use and has connected therewith a plurality of pins 18 connected with the ring 19, said ring and pins acting as guides for guiding the valve in its upward and downward movement. When the bottle is in an upright position the upper surface of valve 6' is flush with the upper edge 8 of the neck 2, but when the bottle is inverted the weight of the fluid will move the valve 6' until the disk 17 is moved toward the tubular member 12 and away from the upper edge 8 of neck 2, whereupon the fluid may freely flow into chamber 16 and from thence out of the bottle. It will of course

be evident that the length of the tubular member 12 may be varied without departing from the spirit of the invention and also the other parts may be changed in size and rearranged within certain limits without departing from the invention.

What I claim is:

1. In a bottle of the character described, a neck, a valve arranged in said neck, an auxiliary neck connected to the first mentioned neck, said auxiliary neck being formed with a guard arranged above said valve, said guard being provided with an annular dividing web which merges into the auxiliary neck and into a tubular section which extends above and below the web, and a disk-shaped hollow member merging into the upper part of said tubular member, said disk-shaped hollow member having apertures facing said web.
2. In a bottle of the character described, a neck portion, a cylindrical valve member arranged in said neck portion formed with a closed top and an open bottom, the sides

of said valve member being formed with a plurality of apertures below the top, a spring rigidly secured at one end to said neck portion and formed with a coil resting substantially centrally of said top for resiliently holding the valve member in a lowered or closed position, and means arranged above the valve and the spring acting as a guard therefor.

3. In a bottle of the character described, a neck portion provided with a projection, a valve member arranged in the neck portion and normally resting on said projection, said valve member having a closed upper end and depending parts acting as guides, a spring connected to said neck portion and extending to near the center of said valve member for normally holding said valve member so that the closed upper end will close said neck portion, an auxiliary neck connected with said neck portion, and a guard arranged in said auxiliary neck.

FRANCISCO QUINTANO CUESTA.
